(57) CLAIM

The ornamental design for a baseball cap having stylized letters and logo, as shown and described.

DESCRIPTION

The FIGURE is a front perspective view of a baseball cap with stylized letters and logo, showing my new design. The evenly dashed broken lines depict portions of the baseball cap with stylized letters and logo which form no part of the claimed design. The dash-dot-dash broken lines depict boundary lines of the baseball cap with stylized letters and logo which forms no part of the claimed design.
